UNITED STATES PATENT OFFICE

169,872

COMBINED TOP AND BACKGUARD CONTROL
PANEL FOR A WASHING MACHINE

Bertrand N. Trombley, Birmingham, Mich., as-
signor to Borg-Warner Corporation, Chicago,
Ill., a corporation of Illinois

Application September 14, 1951, Serial No. 16,633

Term of patent 14 years

(Cl. D49—1)

To all whom it may concern:

Be it known that I, Bertrand N. Trombley, a citizen of the United States, residing in Birmingham, in the county of Oakland and State of Michigan, have invented a new, original, and ornamental Design for a Combined Top and Backguard Control Panel for a Washing Machine, of which the following is a specification, reference being had to the accompanying drawing, forming a part thereof, in which:

Fig. 1 is a perspective view of a combined top and backguard control panel for a washing machine embodying my new design;

Fig. 2 is a front fragmentary elevational view of a portion of a combined top and backguard control panel for a washing machine depicted in Fig. 1;

Fig. 3 is a sectional view taken substantially on the plane of the line 3—3 in Fig. 2;

Fig. 4 is a sectional view taken substantially on the plane of the line 4—4 in Fig. 2; and

Fig. 5 is a sectional view taken substantially on the plane of the line 5—5 in Fig. 2.

The dominant features of my design reside in the portions shown in full lines.

I claim:

The ornamental design for a combined top and backguard control panel for a washing machine, substantially as shown and described.

BERTRAND N. TROMBLEY.
